UNITED STATES PATENT OFFICE.

JACOB KRONHEIM, OF FLINT, MICHIGAN.

METHOD OF UPHOLSTERY.

1,111,966.

Specification of Letters Patent. Patented Sept. 29, 1914.

Original application filed March 15, 1913, Serial No. 754,536. Divided and this application filed September 17, 1913. Serial No. 790,219.

To all whom it may concern:

Be it known that I, JACOB KRONHEIM, a subject of the Emperor of Austria-Hungary, residing at Flint, in the county of Genesee, 5 and State of Michigan, have invented certain new and useful Improvements in Methods of Upholstery, of which the following is a specification, reference being had therein to the accompanying drawings.

10 This invention relates to improvements in upholstery and the method of manufacturing the same.

The object of the invention is to facilitate and cheapen the upholstering of seat backs 15 for vehicles by providing a simple and expeditious method of manufacture, the invention consisting in the matters hereinafter set forth and more particularly pointed out in the appended claims, reference being had 20 to the accompanying drawings in which—

Figure 1 is a plan view of a mold member embodying features of the invention; Fig. 2 is an edge elevation of the same; Fig. 3 is a plan view similar to Fig. 1 showing 25 upholstery and members or forms in operative position; Fig. 4 is a transverse section through Fig. 3 showing the mold within a suitable press; Fig. 5 is an end elevation of a suitable forming table and press with the 30 mold in operative position thereon; Fig. 6 is a plan view of Fig. 5 with parts removed; Fig. 7 is a perspective detail of a finishing strip; Fig. 8 is a detail illustrating the 35 manner of securing the upholstery to the vehicle body; Fig. 9 is a perspective detail illustrating the manner of securing the lower edge of the upholstery to the body seat; Fig. 10 is a vertical section through a vehicle seat showing the manner of securing 40 the upholstery in place thereon; Fig. 11 is a perspective view showing a receiving frame for holding the formed upholstery while the same is being re-formed and adjusted before its application to the vehicle seat; and Fig. 12 45 is a view similar to Fig. 5 of a modified construction of clamping means for the molds.

The subject matter of this application was divided out from an application filed Mar. 15, 1913, Serial No. 754,536.

50 Heretofore it has been the common practice in upholstering seat backs, to form a tufted strip of the proper size and shape, by placing the leather, padding and lining upon a plain flat form which is provided

with means for holding the upholstery buttons with their securing means in position to pierce the material when placed thereon. The strip thus formed is then placed in position upon the vehicle seat back and secured in place, the upper edge or roll being 60 formed in place upon the back and made fast thereto as it is formed. Care and skill are required to properly stretch and form the strip to place upon the back and the operation of securing the edges in place is 65 very difficult and slow.

In order to more accurately form the tufted strip to the curve of the seat arm, and to facilitate the securing of the strip in place, said strip has been molded previous 70 to its application to the seat back, but it was still necessary to use great skill and care in forming the edge roll of the upholstery in place.

The method embodied in this invention 75 consists in tufting a strip of upholstery in the flat and at the same time forming thereon an upper edge roll and properly folding and forming the lower edge and securing the same to suitable securing strips. The 80 strip of upholstery is then bent or formed, and at the same time held against distortion, to conform to the curve of the seat back and arms, and a properly formed finishing strip is made fast to the edge of said 85 roll. The upholstery thus formed and held is then ready to be set in place upon a vehicle seat and made fast thereto by securing the securing strips to the seat bottom and the finishing strip to the upper edge of the 90 back, said finishing strip taking the place of the finishing strip usually provided upon the vehicle seat back.

As illustrating suitable means for carrying out the method of upholstering seat 95 backs embodied in this invention, devices are shown in the accompanying drawings, adapted for use in manufacturing by said method upholstery embodying the invention, but it will be understood that other 100 means may be employed to carry out said method or changes made in the construction or arrangement of parts. In practising the invention, a mold block 1 is provided comprising a central straight section and end 105 sections 2 connected thereto by hinges 3, said sections being formed with a rib 4 along one edge, which rib has in cross-sec-

tion a curved side, and in plan view, an outline which is substantially the same as the outline of the strip of leather which is cut of the proper size and shape to form the 5 facing 5 of the upholstery and of the strip 6 which forms the backing therefor. Distributed over the face of the mold sections are holders 7 in which are placed upholstery buttons 8 with their shanks 9 extending 10 therefrom and so positioned that when the facing and backing strips are placed thereon with a filling 10 of curled hair or other suitable material between them and then pressed down thereon, the buttons will 15 be properly placed to pierce the strips and form the desired arrangement of tufting. To so press the material down upon the button shanks and form it against the curved side of the rib 4, a board 11 is provided to 20 engage the body portion of the upholstery, and edge or margin strips 12 which are formed to conform to the rib, are provided to press the material down upon the curved forming side of the rib to give to that portion of the tufted strip which forms the upper 25 edge of the upholstery the proper rounded form with the edge of the facing laid in proper folds, as shown at 13 in Fig. 3. The board 11 is formed with a series of 30 holes to receive the points of the button shanks when the board is forced down by a suitable press comprising a hand operated screw 14 (see Fig. 4). The strips 12 are pressed toward the mold simultaneously 35 with the board by providing arms 15 on said board extending over said strips.

When the upholstery has been properly formed in the mold by the press, in an extended or flat position and the button 40 shanks have been clenched down upon the backing to hold the tufting, the end edges of the facing and backing are stretched, formed over and made fast to end fastening strips 16 by tacks or other suitable means, 45 and the bottom edges of said facing and backing are also stretched, formed around, laid in plaits and then tacked or otherwise secured to bottom securing strips 17 extending along the back portion of the upholstery 50 and strips 18 along the lower edges of the arm portions. The upholstery is thus formed up in the flat with its edges finished and edge roll formed for application to the vehicle seat.

55 In order that the flat strip of upholstery thus formed may be quickly and easily applied to a vehicle seat and when so applied will have the proper curve to fit the curve of the seat, the said mold block 1 is made 60 of a plurality of hinge connected parts as described, so that the end sections 2 upon which the arm portions of the upholstery are formed, may be turned downward to form said portions around into a shape approximating that of the vehicle seat back

and arms. To so turn and hold the end portions of the mold and form the upholstery down thereon, at the same time holding the rolled or formed edge portion of the upholstery against distortion, a suitable 70 forming table 19, shown in Figs. 5 and 6, is provided to support the mold when removed from the press shown in Fig. 4, and this table is provided with vertical standards 20 at one edge for supporting a cross-bar 21 extending horizontally over the table at a distance above the same. This bar carries a hand screw 22 provided with a foot at its lower end to engage the center margin strip 12 and hold the formed edge 75 of the upholstery firmly against the curved portion of the center section of the mold, so that it can not be distorted when the end or arm portions of the upholstery are folded downward at each side of the table 19 upon the end sections 2 of the mold which are turned downward against stops 23 on the sides of the table. Swinging bars 24 pivotally attached to the ends of the cross bar 21, are adapted to be swung into engagement 80 with the end sections of the margin strips 12 and press said sections firmly against the arm portions of the upholstery along the formed edges thereof to hold said arm portions in place and prevent distortion of the 85 formed edge of the upholstery. These bars 24 are swung toward each other and firmly held by means of a rod 25 passing through said bars and provided with a hand wheel 26 on a screwthreaded end of the rod in engagement with the outer side of one of said bars.

After being formed and clamped in position upon the table 19, a finishing strip 27 shown in Fig. 7, is placed just inside the 105 formed up edges 13 of the facing and backing and said edges tacked or otherwise secured thereto, as shown in Fig. 6. This finishing strip is made to just fit the outer face of the vehicle seat back and arms adjacent to the upper edge thereof, conforming to the curve of said edge in each direction and taking the place of a like strip which is commonly secured to said edge by the body maker when the vehicle body is manufactured.

After the finishing strip has been secured to the edge of the formed upholstery, said upholstery with said strip upon its upper edge and the securing strips 17 and 18 upon 110 its lower edge, is removed from the table, the finishing strip holding the upholstery in its curved shape, and may be at once applied to a vehicle seat by setting it in place thereon with the finishing strip against the 115 outer side of the upper edge of the back and arm portions. The upholstery may then be readily secured in place upon the seat back and arms by nailing or otherwise securing said finishing strip to said edge and the se- 120 130

curing strips 17 and 18 may be nailed to the seat frame or preferably, they are provided with ears 28 formed from sheet metal and provided with openings to receive screws for 5 screwing them to the seat frame, said ears projecting forwardly from said strips beneath the lower edge of the leather of the upholstery so that they may be readily secured in place. When the vehicle seat 10 body is provided with an arm 29 for the attachment of a vehicle top, as shown in Fig. 8, the strip 27 will be cut in two opposite said arm so that the strip may be placed over the edge of the body.

15 Should it be desirable to re-arrange the padding or filling of the edge roll or tufts of the upholstery after it has been formed up as described and removed from the table 19, it may be placed in and secured to an 20 open frame 30, which has a form substantially the same as that of the vehicle seat back and arms. While the upholstery is accurately and firmly held in this frame 30, the workmen may conveniently get at the 25 back side of the upholstery through the frame and with a suitable tool may re-arrange the filling to give a smooth even tufting.

By the method described, upholstery may 30 be made up independently of the vehicle body or seat in such a way that it may be very quickly and accurately secured in place by any workman of ordinary skill and the upholstery itself may be made and formed 35 by unskilled labor with the use of the device described and by following the method set forth. By making the upholstery in the flat so that the tufts may be accurately formed and the folds in the leather accurately made, the work is greatly facilitated 40 and a high grade of work turned out without the necessity for employing skilled upholsterers. The finishing strip 27 not only serves as a member to which the edge of 45 the upholstery is secured after the same has been properly formed to hold it in place, but also holds the body of the upholstery in shape for ready application to the seat.

A modification of the clamping means 50 shown in Fig. 5 is shown in Fig. 12, the screw shaft 22 being provided with a drum 31 on its lower end upon which cables 32 are wound when the hand wheel or the shaft is turned to run the screw down and bring 55 the foot thereon into contact with the center margin strip 12. The opposite ends of said cables are attached to the bars 24 and thus

when the shaft is turned and the cables wound upon the drum, said bars will be swung inward into contact with the end 60 strip 12 and clamp the arm portions of the upholstery. The drum and cables are substituted for the rod 25 and hand wheel 26, and operate to swing the bars 24 simultaneously with the turning of the screw. 65

Obviously changes may be made in the apparatus for carrying out the method described and changes may also be made in the construction of the upholstery, without departing from the spirit of my invention 70 and I do not therefore limit myself to the construction or arrangement of parts or forms shown.

Having thus fully described my invention what I claim is:— 75

1. The method of forming upholstery which consists in placing material in a mold and pressing the same therein to form tufts, then holding the central portion of the material against distortion and bending the 80 ends, and then securing a strip to the formed material.

2. The method of forming upholstery which consists in first placing material to 85 form a strip of upholstery within a mold in an extended flat position and pressing it therein to form tufts and a rounded edge portion, folding and securing the edges of the molded strip, and then holding the formed edge portion against distortion and 90 bending and shaping the molded upholstery strip to conform to the curve of the back and arms of a seat.

3. The method of forming upholstery which consists in first placing material to 95 form an upholstery strip within a mold in an extended flat position and pressing it therein to form a rolled-up edge portion and tufts, then holding the rolled edge portion against distortion and bending the ends of 100 the molded strip to conform to the curving of the back and arm portions of a seat, then removing the molded upholstery strip from the mold and placing it within an open supporting frame to hold it in formed position 105 and re-arranging the material while the upholstery strip is so held.

In testimony whereof I affix my signature in presence of two witnesses.

JACOB KRONHEIM.
